TABLE LAMP

Sergio Gandini, Via Tosio 20, Brescia, Italy

Filed Aug. 5, 1971, Ser. No. 169,605

Term of patent 7 years

Int. Cl. D26—05

U.S. Cl. D48—20 R

FIG. 1 is a perspective view of a table lamp showing my design;

FIG. 2 is a side elevational view of FIG. 1;

FIG. 3 is a front elevational view of FIG. 1;

FIG. 4 is a rear elevational view of FIG. 1;

FIG. 5 is a top plan view of FIG. 1; and

FIG. 6 is a bottom plan view of FIG. 1.

I claim:

The ornamental design for a table lamp, as shown and described.
